UNITED STATES PATENT OFFICE.

JOHAN ALBRECHT, OF BUFFALO, NEW YORK.

BOOT-CRIMPER.

SPECIFICATION forming part of Letters Patent No. 394,748, dated December 18, 1888.

Application filed March 10, 1888. Serial No. 266,799. (No model.)

To all whom it may concern:

Be it known that I, JOHAN ALBRECHT, a subject of the King of Prussia, residing at Buffalo, in the county of Erie and State of New York, have invented certain new and useful Improvements in Boot-Crimpers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention consists in certain improvements in that class of boot-crimpers which are secured to the last and have gripping-jaws for engaging with and holding the edges of the upper while being crimped.

20 I will now proceed to describe the manner in which I have carried out my invention.

In the drawings, Figure 1 is an elevation of my improved crimper. Fig. 2 is a detached detail view, and Fig. 3 shows the last and upper 25 per with the crimper attached.

Referring to the drawings, *a* is the frame or block of the crimper having the longitudinal slot *a'*, which forms on either side the fixed jaws *a²* *a²*, the outer surfaces of which 30 are notched transversely, forming teeth *a³*.

a⁴ *a⁴* are screw-threaded bolts extending out from the side of the frame *a*.

b *b* are the movable jaws, which are loosely pivoted to the sides of the frame at its top 35 edges. Each jaw *b* is provided with an elongated slot, *b'*, through which the screw-threaded bolts *a⁴* *a⁴* pass, the slots being elongated, as shown, to allow sufficient outward play of the movable jaws during their manipulation. The lower inside surfaces of these 40 movable jaws are notched transversely, forming teeth *b²*, similar to those on the fixed jaws *a²* *a²*, which teeth are so placed as to register with the teeth of the fixed jaws *a³*.

45 *c* *c* are thumb-nuts, movable upon the bolts *a⁴* to press the movable jaws against the fixed jaws. The frame or block *a* is provided with a central vertical screw-threaded orifice in which the screw *d* is movable back and forth.

A handle, *d'*, upon the screw *d* serves to turn 50 the same. The lower end of the screw *d* is passed through the slotted plate, and secured therein by the pin *e'*. This slotted plate is secured to the form upon which the leather is shaped by the screws *e²* *e²*. The springs *b³* 55 serve to separate the jaws when the thumb-nuts are loosened.

The operation of crimping with my improved device is as follows: The relative position of the device upon the form is shown 60 in Fig. 3. The leather upper (shown at *g*) is bent over the form, and one side is secured between one set of jaws, as clearly shown in Fig. 1, the edge of the leather being tightly gripped between the jaws *a²* and *b* by means 65 of the thumb-nut *c*. The other side is then pulled tightly toward the opposite set of jaws and placed therein, where it is also tightly clamped. After this is accomplished, the turning of the screw *d* stretches the leather 70 over the form to the required tension.

In crimping devices now in use the gripping of the edges of the upper and the stretching of the same are accomplished simultaneously, making the operation an awkward and 75 difficult one. In my improved device each set of jaws is operated independently of the other, and both sets of jaws are in turn independent of the stretching-screw, thus making the crimping of the leather of the upper much 80 easier and more reliable.

I claim—

A boot-crimper consisting of the slotted frame or block *a*, having the fixed jaws *a²* *a²*, the pivoted movable spring-pressed jaws *b* *b*, 85 each operated independently of the other by separate screw-bolts and thumb-nuts *a⁴* and *c*, and the stretching-screw *d*, secured to the form and operating independently of the two sets of jaws to stretch the leather, substantially as shown and described.

In testimony whereof I have signed my name to this specification in the presence of two subscribing witnesses.

JOHAN ALBRECHT.
